UNITED STATES PATENT OFFICE

JOHN PHILIP WEGE, OF WEST BEND, WISCONSIN, ASSIGNOR TO AMITY LEATHER PRODUCTS CO., OF WEST BEND, WISCONSIN, A CORPORATION OF WISCONSIN

DESIGN FOR A BILL FOLD

Application filed September 26, 1932. Serial No. 45,068. Term of patent 14 years.

To all whom it may concern:

Be it known that I, JOHN PHILIP WEGE, a citizen of the United States, residing at West Bend, in the county of Washington and State of Wisconsin, have invented a new, original, and ornamental Design for Billfolds, of which the following is a specification, reference being had to the accompanying drawing, forming a part thereof.

In the drawing:

Fig. 1 is a front elevational view of a bill-fold embodying my new design; and

Fig. 2 is an end view thereof.

I claim:

The ornamental design for a billfold as shown.

JOHN P. WEGE.
